UNITED STATES PATENT OFFICE.

HENRY OTTO, OF BLOOMINGTON, ILLINOIS.

AIR-PROPELLER.

993,199.

Specification of Letters Patent. Patented Sept. 7, 1909.

Application filed November 14, 1908. Serial No. 402,698.

To all whom it may concern:

Be it known that I, HENRY OTTO, a citizen of the United States, and residing at Bloomington, in the county of McLean and State of Illinois, have invented a new and useful Improvement in Air-Propellers, of which the following is a complete specification.

This invention relates to improvements in propellers and more particularly to a propeller adapted for aerial navigation.

Heretofore it has been usual to construct propellers for aerial navigation along the same lines as those constructed for water navigation, but it has been found that, owing to the greater elasticity and mobility, and less density, of the air, as compared with water, that, with the same speed of the propeller in air as in water, but a comparatively small amount of force can be exerted.

This is due in great measure to the ease with which air passes off from the propeller blades in all directions as they are ordinarily constructed.

The object of this invention is to provide a propeller adapted for aerial navigation which is so constructed that it tends to prevent the air from escaping off from the blades except in one direction, and, by compressing the air causing it to exert greater resistance to the movement of the blades as it escapes from the rear margins thereof with increased velocity.

It is a further object of the invention to provide a propeller in which the blades are strengthened or reinforced at the points where the greatest air resistance is encountered so as to prevent their becoming distorted, and at the same time making it possible to construct the blades of comparatively light material.

The invention consists of the matters hereinafter described in the specification and more fully pointed out and defined in the appended claims.

In the drawings: Figure 1 is a rear elevation of a propeller embodying my invention. Fig. 2 is a front elevation of the same. Fig. 3 is an end elevation of the propeller. Fig. 4 is a side elevation of the same. Fig. 5 is a section taken on line 5-5 of Fig. 2. Fig. 6 is a section taken on line 6-6 of Fig. 3.

As shown in said drawings: A indicates a propeller shaft having a hub *a* rigidly secured thereon, and to which the propeller blades *B-B* are secured in any preferred

manner. As shown, however, said hub is provided with integral attaching plates *a'* to which said plates are rigidly riveted or bolted. Said blades may be of any preferred number, but, as herein shown, but two are employed which are oppositely disposed on the shaft. The forward or air taking edges *b* of said blades extend oppositely from the shaft and at approximately right angles thereto, while the rear edges *b'* thereof extend rearwardly of the shaft and are shorter than the edges *b*. The blades are concaved on their rear sides and the general plane thereof lies at an angle of approximately 35 degrees to the shaft with the greatest curvature or convexity thereof near its rear, as shown more clearly in Figs. 3 and 5.

On the outer end of each blade and on the rear side thereof is a retaining flange *b'*, which increases in width from the forward edge of the blade toward the rear thereof. Owing to the fact that the edge *b'* is shorter than the edge *b* of the blade it is obvious that the rear end of said flange is nearer the shaft than is the forward end thereof, with the result that when air enters the blade it is caught by said flange and forced or compressed toward the shaft in its effort to escape from the end of the blade, thereby causing the air to leave the blade from the rear edge *b'* with increased velocity, and as a consequence to exert greater forward pressure on the blade. The edges of the blades, as well as the edges of the flanges, are reinforced by a strip of metal *b''* having sufficient rigidity to prevent the blade from bending under the strain to which it is subjected.

Obviously a propeller embodying my invention is adapted to exert great force upon the air by reason of the concentration of the air upon the blades, and obviously also many details of form and construction may be varied without departing from the principles of my invention.

I claim as my invention:

1. In a device of the class described the combination with a propeller blade of a rearwardly and inwardly directed flange on the rear face thereof, said flange increasing in width from its forward end rearwardly.
2. In a device of the class described the combination with a shaft of propeller blades thereon, said blades being concaved on their rear side, and a flange on the rear face of

each blade extending from the front edge thereof rearwardly and toward said shaft and increasing in width toward its rear end.

3. In a device of the class described the combination with a shaft of concaved propeller blades thereon, and a flange on the concave side of each blade adapted to compress the air and direct it to the rear edge of the blade said flange increasing in width from its front end rearwardly.

4. In a device of the class described the combination with a shaft of propeller blades thereon, a forwardly tapering flange on the

outer end of each blade extending from the front edge thereof rearwardly and approaching nearer to the shaft at its rear end than at its forward end, and a reinforcing strip on the edges of said blades and flanges.

In witness whereof I have hereunto subscribed my name in the presence of two witnesses.

HENRY OTTO.
